UNITED STATES PATENT OFFICE.

ORWELL C. REEVES, OF TOLEDO, OHIO, ASSIGNOR TO TOLEDO SCALE COMPANY, OF
TOLEDO, OHIO, A CORPORATION OF NEW JERSEY.

DESIGN FOR A SCALE CASING.

Application filed June 20, 1924. Serial No. 9,918. Term of patent 14 years.

To all whom it may concern:

Be it known that I, ORWELL C. REEVES, a citizen of the United States, residing at Toledo, in the county of Lucas and State of Ohio, have invented a new, original, and ornamental Design for Scale Casings, of which the following is a specification, reference being had to the accompanying drawing, forming a part thereof.

Figure I is an elevational view of a scale showing my new design;

Figure II is an elevational view taken at right angles to Figure I.

I claim:

The ornamental design for a scale casing as shown.

ORWELL C. REEVES.
